Primary Examiner — Richard E Chilcot*(74) Attorney, Agent, or Firm* — Banner & Witcoff, Ltd.**(57) CLAIM**

The ornamental design for a display screen with graphical user interface, as shown and described.

DESCRIPTION

The FIGURE is a front view of a display screen with graphical user interface showing a new design shown on a device. The broken line showing of the remainder of the graphical user interface, the border of the display region, and the remainder of the device is for environmental purposes only and forms no part of the claimed design.
